NONREFILLABLE BOTTLE AND UNIT
THEREFOR

Thomas Leonard MacBean, New York, N. Y.

Application June 3, 1935, Serial No. 24,756

9 Claims. (Cl. 215—23)

The invention relates to non-refillable bottles and has for its objects to provide certain new and useful improvements in devices of this character.

5 An important object of the invention is to provide a device adapted to be inserted as a unit into the neck of a filled bottle and having a valve or closure member and operating member therefor, the relative specific gravities of said valve and 10 operating members being such that the latter holds the valve to its seat in all positions of the bottle except when liquid is actually being dispensed from the bottle. This insures against refilling of the bottle after the contents or any part 15 thereof has once been dispensed or consumed.

A further object of the invention consists in the provision of an improved device for the purpose described which is adapted to be conveniently inserted in a bottle neck, said device including automatically operative or expansible means to secure 20 the device within the interior of the bottle so as to insure against its subsequent removal therefrom.

A still further object consists in providing a 25 non-refillable bottle unit composed of a plurality of relatively insertable interengaging members, the engagement of one with the other serving to automatically lock the same together to the end that after the assembled unit has been inserted 30 within the neck of a filled bottle, said unit may not thereafter be disassociated and partially or entirely removed from the bottle neck to permit access to the valve structure or unauthorized refilling of the bottle.

35 A still further object is to provide a non-refillable bottle unit or device which is composed of few parts capable of economical manufacture and convenient assembly, certain of which parts cooperate with the liquid within the bottle to maintain 40 the proper relationship between the valve and its seat. This is to the end that liquid may be dispensed from the bottle only when the latter is in tilted or pouring position, the effect of any attempt to refill the empty bottle when in 45 inverted position resulting in immediate seating of the valve, thereby insuring against such unauthorized refilling.

With such objects in view, as well as other advantages which may be incident to the use of the 50 improvements, the invention consists in the parts and combinations thereof hereinafter set forth and claimed, with the understanding that the several necessary elements constituting the same may be varied in proportions and arrangement 55 without departing from the nature and scope of the invention.

In order to make the invention more clearly understood there are shown in the accompanying drawings means for carrying the same into practical effect, without limiting the improvements,

in their useful applications, to the particular constructions which, for the purpose of explanation, have been made the subject of illustration.

In said drawings:

Figure 1 is a view in vertical section through a 5 bottle neck and showing a preferred embodiment of the invention applied thereto.

Figure 2 is a similar view showing the non-refillable bottle unit in partially inserted position 10 within the bottle neck.

Figure 3 is a similar view showing a slightly modified valve or closure construction.

Figure 4 is a transverse section on line 4—4 of Fig. 1.

Figure 5 is a view similar to Fig. 1 showing a 15 modified form of non-refillable closure device.

Figure 6 is a transverse section on line 6—6 of Fig. 5.

Figure 7 is a view similar to Fig. 1 showing a 20 still further modified form of valve or closure construction.

Figure 8 is a view similar to Fig. 1 showing a 25 still further modified form of non-refillable closure device.

Figure 9 is a transverse sectional view on line 25 9—9 of Fig. 8.

Figure 10 is a similar view on line 10—10 of Fig. 8.

Figure 11 is a fragmentary detail view of the structure shown in the upper part of Fig. 8 when 30 applied to a bottle designed to be closed by a screw cap with or without the usual frangible sealing ring.

Referring to the drawings and with particular reference to Figs. 1 and 2, the bottle or container 35 to which the invention is designed to be non-removably applied is indicated at 1 and embodies the usual integral threads or projections 2 for receiving any suitable form of removable outer closure cap, not shown. The inner surface 3 of the bottle neck extends downwardly and thence flares outwardly as indicated at 4 in the usual manner to merge with the body wall, not shown, of the bottle.

The non-refillable device comprises an outer 45 hollow housing, sleeve or shell 5 and an inner housing member generally indicated at 6. The shell member 5 is preferably constructed of sheet metal of suitable resiliency so as to cooperate with the housing to lock the parts in position against removal within the bottle neck. Said shell member is substantially of cup-shaped formation and is provided at its upper end with a lateral flange 7 terminating in a depending substantial outer flange portion 8 proportioned 50 to snugly engage the top of the bottle neck for which it is designed. Said shell further comprises an integrally formed inwardly and upwardly extending conical wall 9 terminating in a substantially central circular aperture 10. 60

The lower portion of the shell 5 further comprises an expandable skirt portion 9a, the expansion of which is facilitated when the complete unit is assembled by providing such skirt portion with a plurality of elongated substantially vertically disposed spaced slots 9b extending from the skirt portion through the return bend 9c and terminating short of the circular aperture 10. The expansion of the skirt portion 9a into engagement with the bottle wall is facilitated by the slots 9b which under radial pressure expand from the position shown in Fig. 2 into that shown in Figs. 1 and 3.

The inner housing member 6 is also preferably constructed of sheet metal, is substantially cup shaped and is proportioned to snugly engage the inner wall of the shell 5. The upper end of the housing is extended inwardly as at 11 and terminates in downwardly and outwardly extending flange portions 12 and 13 together defining the discharge opening of the bottle. The housing further comprises a lower cup shaped member 14 terminating in an upper peripheral flange 15 and having its intermediate portion flanged inwardly as at 16 to provide a valve seat for the closure device. Below the valve seat the housing is of reduced diameter at 17 and is outwardly beaded at 18 to constitute a continuous projection adapted to engage the walls of the aperture 10 of the shell member 5. The lower portion of the housing terminates in an inwardly tapered conical member 19 having lateral apertures 20 and a lower reduced opening 21 formed by rounding the lower extremities 22 of the conical wall 19. The housing 6 further comprises an intermediate substantially conical member 23 having a reduced upper portion 24 which is closed at its upper end and provided with a plurality of lateral apertures 25. The upper portion of the housing is shaped to receive an inner lining 26 preferably of porcelain or the like, which may be molded and hardened within the housing as illustrated. Said lining 26 includes a plurality of inwardly extending substantially vertical rib members 27 terminating at their upper ends in inwardly projecting lugs 28 defining shoulders or stops to limit upward movement of a freely movable closure or safety disk member 29 normally seated on the closed upper end of the intermediate member 24 of the housing. The disc member 29 may be peripherally serrated or notched to permit liquid to be discharged past the disc into the discharge opening 12 of the closure. The porcelain or other refractory lining 26 is securely locked within the upper portion of the housing 6, by means of the outwardly flared flange portions 13 of the housing. The upper sleeve portion of the sheet metal housing 6 is suitably secured to the intermediate portion 24 thereof and to the lower cup-shaped portion 14 by means of pins 31 or other locking means, which are seated in adjacent flange portions of the respective members of the housing to constitute a unitary assembly including the refractory lining 26, safety disk 30 and the valve mechanism which will now be described.

In Figs. 1 and 2 the valve or closure member is illustrated as consisting of a disk 32 which may be of hollow imperforate sheet metal as illustrated, with or without an inner packing of cork or other similar material, to the end that the valve disk will act in the manner of a float when in contact with a liquid. A valve operating member is indicated at 33, and in the

form illustrated consists of a hollow or other ball or sphere of less specific gravity than the liquid 34 within the bottle, so as to float on the surface thereof, but of preferably greater specific gravity than that of the valve disk member 32. 5 The valve and valve operating members 32 and 33 are secured together by a flexible cord member 35 secured at its opposite ends to said members and preferably consisting of finely spun silk or other material which is not subjected to 10 swelling or roughening as a result of contact with the liquid. The flexible cord 35 is designed to move freely through and relative to the restricted aperture 21 of the housing member and not retarded in its movement thereby, so as to 15 quickly and accurately govern the movements of the valve disk 32 in respect to the seat 16 of the latter.

In assembling the unit the flexible cord having its lower end secured to the valve operating member 33, is threaded into the smooth aperture 21 of housing member 14 and is then secured at its upper end as at 36 to the valve or closure 32. The latter is inserted into its housing through the upper end 15 of the latter. The safety disk member 29 is inserted from below into the upper portion 6 of the housing having the preformed refractory or porcelain lining 26 therein, the intermediate member 24 of the housing is placed in position and the three members are permanently secured together as by means of the pins 31 or other securing means. The described housing assembly is or may be thereafter partially positioned within the outer shell member 5 from above as best seen in Fig. 2 until the rib or bead 18 of the housing engages the aperture 10 of the shell. A thin paper or other sleeve-like packing 37 may be positioned between the shell and bottle neck to insure against leakage of liquid from the bottle at this point. If desired, the described 40 gasket may consist of cement or like material which may be extended over the lip of the bottle as indicated at 38. In the event cement is used, the same also constitutes an additional means for securing the sleeve to the bottle. 45

From the position shown in Fig. 2 the assembly is completed by forcing the housing further into the shell into the position shown in Fig. 1. In the latter position it will be observed that further downward movement of bead 18 after contact 50 with the shell results in expanding outwardly the lower portion of the shell 5 into close frictional engagement with the curved wall 4 of the bottle below its neck, thereby insuring against 55 subsequent removal of the sleeve from the container, the expansion of the slots 9b facilitating such locking engagement. The outer wall of the housing 6 is provided with a peripheral recess 39 adapted to receive and seat a resilient expandible ring member 40 of spring metal or the like, which latter may be compressed to permit its reception within the upper open end of the sleeve. When the assembly of the housing within the shell is complete the recess 39 registers with a corresponding annular recess 41 provided in the inner wall of the shell 5. At this point the expandible ring member 40 springs outwardly into said latter recess. In expanded position, it will be observed that the dimensions of the recess 41 are such 70 that the same will not house the complete width of the ring member. In this manner portions of the upper and lower edges of said ring engage adjacent walls of both recesses 39 and 40 to thereby securely and irremovably lock the sleeve 75.

and housing together and effectually prevent the housing from being subsequently removed from the sleeve after the latter has been securely locked in the manner above described from movement relative to the bottle neck.

It will be observed that when the bottle is in upright position, the valve or closure member 32 will be normally seated to prevent access to the interior, and the action of the operating member 33 through cord connection 35 tends to pull the valve 32 tightly against its seat, regardless of whether member 33 is floating on the surface of the liquid as in a filled bottle, or depending freely within the bottle as when the contents of the latter are completely or partially consumed. The same action would be obtained in holding the valve to its seat were the operating member 33 a weight instead of a float, in which latter event the valve would be held to its seat through cord connection 35 by the weight of member 33 depending within the bottle or submerged in the liquid of a filled bottle.

In pouring position, the force of the liquid entering through apertures 20, in addition to gravity, unseats the valve and the liquid is dispensed from the bottle through apertures 25 and past the safety disk member 30 between the spaced rib members 27 into the discharge opening 12. The function of the safety disk 30, which is freely movable between the shoulders 28 and the top of housing member 24, is to prevent access to the valve 32 to hold the same open by means of a wire or other implement which otherwise might be inserted into mouth of the bottle and threaded into one of the openings 25.

In the event an effort is made to refill the bottle the valve member 32 being seated prevents such unauthorized filling. In the event the empty bottle is first inverted to unseat the valve the pressure of the incoming liquid immediately forces the valve member against its seat.

The expandible ring member 40 is preferably secured together at its end by a pin and slot connection 42 (Fig. 4) to limit outward expansion thereof to aid in maintaining the ring in position on the housing 6 on shell 5 prior to and during assembly of the parts.

In the construction shown in Fig. 3 a modified valve and seat is shown, the latter constituting a conical inwardly tapered wall 43 on the lower member 14a of the housing 6a. The valve member consists of a truncated spherical member 32a normally in engagement with the conical seat 43 and controlled in respect to its movement thereagainst by the operating member 33a which is illustrated as constituting a float of less specific gravity than the valve 32a. As in the embodiment of Figs. 1 and 2 the valve operating member 33a may comprise if desired a weight member instead of a float.

In the embodiment illustrated in Figs. 5 and 6 a substantially all porcelain construction is illustrated with a slightly modified form of valve and operating members. The shell 5b is molded from porcelain or the like and includes a preferably integral intermediate wall 44 defining an aperture 45 normally covered by a freely movable porcelain safety disk member 30b having peripherally spaced apertures 46 and upper radially disposed spaced rib members 47. This construction of the safety disk 30b permits the flow of liquid from the interior of the bottle through the discharge opening 12b of a closure member 48 also constructed of porcelain and having a lower

conical seat 49 to receive the disk 30b when the bottle is in pouring position. The porcelain shell 5b is secured to the bottle neck by flanged paper gasket member or suitable cement packing indicated at 31b. After the safety disk is positioned 5 the closure 48 may be moved inwardly relative to the shell and securely locked against subsequent removal by means of an expandible ring member 40b arranged in aligned recesses in the closure and shell and operative in a manner similar to 10 the ring 40 (Figs. 1 and 2). The free seating of the safety disk 30b and the smooth refractory nature of the same prevents any possibility of drilling through the same to obtain access to the valve, as the disk will spin when in contact with 15 the drill. This member also prevents access to the valve parts of the bottle by means of a flexible wire or the like. The valve seat member 16b is also formed of porcelain and after insertion within the shell is locked in position by means of 20 an expandible ring member 50 similar to the ring 40b. The valve 32b is controlled relative to its seat by a weight member 33b of porcelain, steel or the like which depends freely by means of flexible cord member 35 to an aperture 22b defined 25

by the lower ends of a plurality of depending and inwardly inclined rod members or wire supports indicated at 51 and which have their upper ends seated as at 52 in the material of the valve seat element 16b. This element is further provided 30 with a peripheral recess 53 in which are anchored a plurality of spaced resilient leaf spring elements indicated at 54. An expandible resilient ring member 55, which may be substantially triangular in cross section, is also adapted to seat within 35 the recess 53 and is urged downwardly and outwardly by the spring elements 54. The ends of the ring member 55 may be cut away as shown at 56, 57 (Fig. 6) and held together within elastic limits by means of a pin 58 having one end 40 in engagement with a slot 59 in the opposite end of the ring. The inner inclined wall of the ring member 55 seats against a similarly inclined wall portion 60 of the member 16b so that the tendency of springs 54 is to expand the ring as it is 45 forced downwardly along the inclined surface 60. In this manner the shell 5b is locked in position within the bottle neck after insertion therein by the frictional engagement of the ring 55 with the outer flaring inner wall surface 4b of the bottle 50 below its point of least diameter. The relation of the valve and operating members 32b and 33b to permit dispensing of the bottle contents and to prevent unauthorized refilling is the same as in respect to the former described embodiments, 55 with the exception that the operating member 33b is illustrated as comprising a weight submerged within the bottle contents, rather than a float. If desired a float may be substituted for the weight, as in Figs. 1 and 2.

The embodiment illustrated in Figure 7 is similar to that in Figures 5 and 6 with the exception that the valve operating member 33c is illustrated as constituting a float preferably of greater specific gravity than the valve disk 32c, so as to draw 65 the valve firmly against its seat 43b. The valve is held on its seat due to the tendency of the float to rise in the liquid through the flexible silk cord connection 35. The weight of the member 33c performs a similar function after the contents of 70 the bottle have been consumed below the free pendant movement of the member 33c. In order to assist the valve 32 to quickly unseat when dispensing the contents of the bottle, the valve is provided with a hollow shell or cup-like member 75

61 which immediately fills with liquid during the act of pouring. This added weight to the valve or closure disk 32c enables it to quickly overcome the weight of the member 33c and any tendency of the latter to retain the valve on its seat. Any attempt to refill the bottle in this embodiment would result as in Fig. 5 in quickly forcing the valve against its seat, regardless of the position of the bottle, to prevent such unauthorized refilling.

5 In the embodiment illustrated in Figs. 8 to 11 inclusive, the insertable unit indicated at 65 is preferably preformed of porcelain or other vitreous material and may if desired be constructed of bakelite, beetlware or like material, which can

10 be made acid and alcohol proof. Said insertable member 65 may be molded as separate units consisting of an upper member 66 and a lower member 67 which are subsequently integrally united in a cleavage line or joint indicated at 68 to

15 provide a unitary structure after the valve member 74 has been assembled on its seat 69. The lower portion of the part 67 of vitreous unit 65 is provided with radially extending and communicating pouring channels 70 and 71 spaced

20 apart by wall portions 72 in order to facilitate the discharge of the bottle contents into the valve chamber 73. The wall portions 72 are centrally apertured as at 72a and are rounded at their lower extremity to provide or constitute a seat

25 ring 72b. As in other embodiments of the invention, the valve member 74 may constitute a float and is secured by flexible connection 75 to

30 weight or float member 76, the latter controlling the movement of the valve toward and from its seat, depending upon whether liquid is being poured from or attempted to be forced into the container.

35

When the bottle is inverted, the ball or weight member 76 rolls or gravitates into the apertured seat ring 72b and remains there while the liquid is being poured until the bottle is returned to a point where the action of gravity permits the ball to roll out and close the valve. With the member 76 in or adjacent the seat ring while 40 pouring, its pull on the closure member or valve 74 through flexible connection 75 is relieved so that the liquid has only to overcome the buoyancy of the closure member itself. The loosely seated safety disc 78 is substantially similar to 45 previously described embodiments and is provided with upper circumferentially spaced lugs indicated at 79 to prevent the disc falling against and closing the dispensing aperture 80 and further permit a free flowing of the liquid around 50 the serrated edges 81 of the disc and through the openings maintained by said lugs.

The unit 65 is securely cemented within the neck of the bottle and if desired may include a thin paper gasket 82 cemented or interposed between the member and the bottle neck to provide a secure fluid tight union. When the unit has been inserted to its full extent as shown in Fig. 8, the split wedge ring 83 expands radially under the influence of a plurality of coil spring members 84, or any suitable type of spring member. The springs 84 bearing on the upper surface of the wedge ring cause the lower conical surface of the latter to slide downwardly on the flared wall 85 on which the ring seats until the outer surface of the ring engages and locks against the outwardly flared inner surface 4 of the bottle wall.

The embodiment shown in Fig. 8 may be provided with a cork within the dispensing aperture 80 with or without the usual screw cap closure

shown at 87 in Fig. 11. In Fig. 11 the vitreous insert member 65 terminates flush with the top wall of the bottle neck as illustrated to permit the bottle to be closed by the usual screw cap 87 with or without an interposed sealing gasket 88 or other disk seal. 5

In all illustrated embodiments of the invention the operating member 33 may operate either as a float in which case it should be lighter than its own displacement in liquid or it may be of metal or other substance heavier than its own displacement in liquid. Where the operating member is lighter than liquid, and operated as a float, it should be slightly heavier than the closure member, and where the operating member is heavier than its displacement in liquid, it should also be slightly heavier than the closure member. When the device is placed in the neck of a bottle and securely fastened therein, the action of the operating member either as a float or a weight tends to pull the closure member against the valve seat thereby preventing the introduction of any liquid into the bottle and when it is desired to pour liquid from the bottle the weight of the liquid against the face of the closure member overcomes the slight variation in weight or buoyancy as the case may be and forces the closure member away from the seat permitting the liquid to pass between the sides of the closure member and the sides of the casing thence by a circuitous channel around the safety disk to the opening at the mouth of the bottle, at the same time sufficient air is admitted through the upper part of the same channels to prevent the forming of a vacuum within the bottle which would retard the flow of the liquid. In either case, if an attempt is to be made to refill the bottle in its normal or vertical position, the closure member of its own weight falls against the seat which is further enhanced by the weight or buoyancy of the operating member and prevents any material passing into the bottle. Any pressure applied in an attempt to force liquid through serves only to close the valve tighter. If it is attempted to refill the bottle in an inverted or any other position, the weight of the operating member, where it is heavier than its displacement in liquid, plus the buoyancy of the closure member forces the closure member against the valve seat thereby preventing the flow of liquid into the bottle. Where the operating member is lighter than its displacement in liquid, its buoyancy, plus the buoyancy of the closure member acts in the same way and prevents the introduction of any liquid into the bottle.

It is also important that the operating member **33** shall not come in contact with the sides of the bottle nor be obstructed in its free action of movement either as a weight or float in pulling the closure member into position.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof. 60 65

What is claimed is:

1. In a non-refillable bottle the combination of
a housing insertable within the bottle neck, said
housing having a valve seat, a valve member con-
fined by said housing and movable towards and
away from said seat, a valve operating member
70
75

flexibly attached to said valve and disposed on the opposite side of said seat, the relative specific gravities of said valve and operating members being such that the operating member through 5 said flexible attachment will move the valve member against its seat to prevent access to the interior of the bottle at all times and to permit withdrawal of a pre-filled liquid only when a filled bottle is in tilted position, expansible means 10 carried by said housing and adapted on insertion of the latter to engage the bottle wall below and radially outwardly from the neck wall, for preventing the removal of the housing from the bottle, and means carried by said housing for 15 locking said expansible means in expanded position.

2. In a non-refillable bottle the combination of a housing insertable within the bottle neck, said housing having a valve seat, a valve member confined by said housing and movable towards and away from said seat, a valve operating member flexibly attached to said valve and disposed on the opposite side of said seat, the specific gravity of said operating member being greater than the specific gravity of said valve, whereby said operating member through said flexible attachment will draw the valve member against its seat to prevent access to the interior of the bottle at all times and to permit withdrawal of a pre-filled liquid only when a filled bottle is in tilted position, expansible means carried by said housing and automatically operative when the housing is inserted to engage the bottle wall below the neck for preventing the removal of said housing from the bottle, and reciprocal means carried by said housing for engaging said expansible means and holding the latter in expanded position against the bottle wall.

3. In a non-refillable bottle the combination of 40 a sleeve member insertable within the bottle neck, said sleeve having means for engaging the interior of the bottle below said neck to prevent removal of the sleeve therefrom, and a housing including a valve and valve seat adapted to be inserted within said sleeve, said housing having means operable when said housing is inserted to move said engaging means of the sleeve member into locking engagement with the interior wall of the bottle to prevent subsequent removal of 50 the sleeve and housing therefrom.

4. In a non-refillable bottle the combination of a sleeve member insertable within the bottle neck, said sleeve having means for engaging the interior of the bottle below said neck to prevent removal of the sleeve therefrom, a housing including a valve and valve seat adapted to be inserted within said sleeve, said housing having means operable when said housing is inserted to move said engaging means of the sleeve member into locking engagement with the interior wall of the bottle, and means disposed between said sleeve member and the bottle neck to prevent relative movement thereof and the passage of fluid therebetween.

65 5. In a non-refillable bottle the combination of a sleeve member insertable within the bottle neck, said sleeve having means operative to engage the interior of the bottle below said neck to prevent removal therefrom, a shell member adapted to be inserted within said sleeve, said shell including a valve seat, a valve confined within said shell and movable relative to said seat, said shell having means engageable with said expansible means to move the latter into interlocking engagement

with the interior wall of the bottle at the limit of insertion of the housing within said sleeve, and locking means operable by the insertion of said housing into said sleeve to secure said sleeve and housing together against relative displacement. 5

6. In a non-refillable bottle the combination of a sleeve member insertable within the bottle neck, said sleeve having automatically expansible means for engaging the interior of the bottle below said neck to prevent removal therefrom, a shell member insertable into said sleeve, said shell including a valve seat, a float valve confined within said shell and movable towards and away from said seat, said shell having a portion engageable with said expansible means to move the latter into interlocking engagement with the interior wall of the bottle at the limit of insertion of the housing within said sleeve, locking means operable by the insertion of said housing into 10 said sleeve to secure said sleeve and housing together against relative displacement, and means carried by said shell and flexibly attached to said valve for holding the latter on its seat except when the contents of the bottle are poured 15 therefrom.

7. In a non-refillable bottle the combination of a sleeve member insertable within the bottle neck, said sleeve member having automatic means for engaging the interior wall of the bottle below 20 said neck to prevent removal of the inserted sleeve therefrom, a valve seat on said sleeve member, a valve housed within said sleeve and movable towards and away from said seat, means carried by said valve member and responsive to the liquid 25 contents of the bottle for controlling the position of said valve relative to its seat, and means loosely confined within said sleeve member for permitting the passage of liquid therethrough and for preventing access to said valve from the outer 30 end of the inserted sleeve member.

8. In a non-refillable bottle the combination of a sleeve member insertable within the bottle neck, said sleeve member having means for engaging the interior wall of the bottle below 45 said neck to prevent removal of the sleeve therefrom, a valve seat on said sleeve member, a valve housed within said sleeve and movable towards and away from said seat, means carried by said valve member and responsive to the liquid 50 contents of the bottle for controlling the position of said valve relative to its seat, and means carried by said sleeve for normally centering said valve controlling means relative to said valve and valve seat. 55

9. In a non-refillable bottle the combination of a porcelain sleeve member insertable within the bottle neck, said sleeve member having means for engaging the interior wall of the bottle below said neck to prevent removal of the sleeve therefrom, 60 a valve seat on said sleeve member, a valve housed within said sleeve and movable towards and away from said seat, means carried by said valve member and responsive to the liquid contents of the bottle for controlling the position of said valve relative to its seat, means carried by said sleeve for normally centering said valve controlling means relative to said valve and valve seat, and means loosely confined within said sleeve member for permitting the passage of liquid therethrough 65 and for preventing access to said valve from the outer end of the inserted sleeve member. 70
